UNITED STATES PATENT OFFICE.

KARL ALBERT FREDRIK HIORTH, OF CHRISTIANIA, NORWAY.

ELECTRICAL INDUCTION-FURNACE.

1,099,440.

Specification of Letters Patent.

Patented June 9, 1914.

Application filed October 8, 1913. Serial No. 794,026.

To all whom it may concern:

Be it known that I, KARL ALBERT FREDRIK HIORTH, a subject of the King of Norway, residing at Christiania, Norway, have invented certain new and useful Improvements in Electrical Induction-Furnaces; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to electric induction furnaces of the disk transformer type and has for its object an improvement by means of which such furnaces are made more suitable for metallurgical purposes.

20 In induction furnaces of the disk transformer type the bath is arranged around the iron core and between the co-axial primary coils in such manner, that the bath is wholly or partly covered by the upper primary coil.

25 Therefore this latter must either in one manner or another be removed, when the various metallurgical operations such as the slag treatment, the charging and the like is to take place or the metal bath must be provided with extensions, not covered by the upper primary coil.

According to the present invention the primary coil is arranged in such manner that the above mentioned drawbacks are avoided the bath being freely accessible. This is obtained by giving the upper and the lower primary coil different diameters, one of the coils having a diameter greater than that of the melting bath and the other 40 coil having a smaller diameter than that of the bath, so that the annular center line of the bath is situated substantially on the conical surface through the center lines of the two coils and about straight between these latter. By this arrangement is obtained firstly that the bath will be easily accessible so that operations such as the working of the slag supplementary addition of charge and the like could be carried out

45 without the upper coil being lifted as is the case with known furnaces of this type and secondly the construction of the furnace becomes simpler and cheaper especially on account of the fact that there are no movable 50 connections between the coils themselves or between the coils and the supply conduits.

The coils being stationary the inductance of the furnace will always be constant and at the same time the great variations in load caused by lifting and lowering the coils are avoided. Further it is also made possible to arrange the bath much nearer to the upper yoke of the cores so that the cores could be made shorter, this effecting a saving of iron and also an improvement in the difference of phase mainly owing to the fact that the iron is brought into the path of the stray field of the coil parts, which are situated immediately below the yoke thereby preventing some lines of power from straying.

Considered as a transformer the furnace is in possession of the advantages of the prior furnace of the disk-transformer type, the upper and the lower coil on each leg as a whole acting in substantially the same manner as two coils of the same diameter as the bath. The coil therefore retains the character of a disk winding with divided coils. The dynamical action of the two coils on the bath partly balance one another so that the inclination and the radial movement of the bath is no greater than in the prior furnace.

Experience shows, that the steel when breaking through the fireproof lining always takes its way inward to the magnet (along the line x, y on the drawing) and downward. By the present arrangement the lower coil will therefore be better protected against destruction when such breaking through occurs than in furnaces having the coil directly under the bath. As the upper coil may be moved nearer to the bath the thick cover (about 100 mm.) being not interposed— $\cos \varphi$ will be as favorable as possible. By this arrangement the cooling of the upper coil will be more efficient than by coils above the cover.

An embodiment of the invention is diagrammatically illustrated in the accompanying drawing in connection with a furnace of the disk transformer type.

Figure 1 shows diagrammatically a vertical sectional view of the furnace. Fig. 2 is a plan view partly in section. Fig. 3 shows a section along the line 3—3, Fig. 2.

In the example shown A is the iron core, B the upper and C the lower primary coil D is the melting bath, comprising in known manner an annular channel surrounding each of the core legs, both being connected

with a widened central bath. As will be seen each of the annular channels of the metal bath is arranged in such manner that an oblique line through the sectional surfaces of the two coils intersects the sectional surface of the melting bath. At the top the melting bath is quite free and easily accessible at every point. L is a cover for the annular channels containing the melting bath. As the lower primary coils should not be so arranged as to intersect one another and as it is not advantageous to make the distance between the legs of the core too large the lower greater coils are somewhat flattened on the inside as shown in Fig. 2. Preferably about $\frac{3}{4}$ of the circumference is made circular and concentrical with the upper coil, while $\frac{1}{4}$ of the circumference is flattened.

20 Claims.

1. In an electrical induction furnace, a magnetic core, a furnace having a channel embracing the core to provide for the melting bath, and two flat conductor coils embracing the core and lying in substantially parallel planes, one of said coils having an outer periphery less than the inner periphery of the channel, and the other of said coils having an outer periphery greater than the inner periphery of the channel, and one of said coils lying wholly below the plane of the top of the channel and the other of said coils lying wholly below the plane of the bottom of the channel; substantially as described.

2. In an electrical induction furnace, a magnetic core, a furnace having a channel embracing the core to provide for the melting bath, and two conductor coils embracing the core, one of said coils lying near the plane of the top of the channel, and the other of the coils lying below the plane of the bottom of the channel, and the conductor parts of the two coils lying at different distances from the core so that an imaginary straight line through the centers of the conductor parts passes through the lower part of the channel; substantially as described.

3. In an electrical induction furnace, a magnetic yoke, a furnace having a channel 50 with a central portion extending through the yoke and branches extending in opposite direction outside of the yoke to provide for the melting bath, two conductor coils embracing individual sides of the yoke and 55 lying near the plane of the top of the channel between the central portion and the branches of the channel, and two other conductor coils embracing the individual sides of the core and lying wholly below the plane 60 of the bottom of the channel, the conductor parts of the lower coils lying on arcs of greater radius than that of the upper coils, so that the lower part of said branches of the channel lies on the surface of an imaginary cone passing through the conductor parts of the upper and lower coils, substantially as described.

4. In an electrical induction furnace, a magnetic yoke, a furnace having a channel 70 for the melting bath, and two conductor coils embracing the opposite sides of the yoke, each of said coils having a flattened portion passing between the sides of the yoke to provide room in the same plane for 75 the other coil without overlapping therewith; substantially as described.

5. In an electrical induction furnace, a magnetic yoke, a furnace having a channel for the melting bath, and two conducting 80 coils embracing the opposite sides of the yoke, each of said coils having a flattened portion passing between the sides of the yoke to provide room in the same plane for the other coil without overlapping therewith 85 and having a remaining portion extending substantially around three-quarters of a circle; substantially as described.

In testimony that I claim the foregoing as my invention, I have signed my name in 90 presence of two subscribing witnesses.

KARL ALBERT FREDRIK HIORTH.
